MOBILE TOWER WITH ELEVATOR FOR MAKING OVERHEAD ASSEMBLIES

Campbell Allen Harlan, Birmingham, Mich.

Application December 15, 1952, Serial No. 326,028

9 Claims. (Cl. 214—103)

The present invention relates to apparatus for making overhead assemblies.

It is an object of the present invention to provide apparatus for making overhead assemblies comprising a tower having wheels at its lower end by means of which it may readily be moved over the ground or floor.

It is a further object of the present invention to provide a movable tower having at its upper end a platform for supporting a workman and a protective rail surrounding the platform.

It is a further object of the present invention to provide a tower of the character described having a trackway extending from top to bottom thereof along one side, and a carriage movable on said trackway.

It is a further object of the present invention to provide a tower of the character described including a trackway which is inclined inwardly and upwardly.

It is a further object of the present invention to provide a tower of the character described including a carriage in which the carriage is provided with track engaging means spaced substantially below the upper side thereof to permit movement of said carriage to a position substantially above the upper end of said trackway.

Other objects and features of the invention will become apparent as the description proceeds, especially when taken in conjunction with the accompanying drawings, wherein:

Figure 1 is a front elevation of a tower constructed in accordance with the present invention.

Figure 2 is a side elevation of the tower shown in Figure 1.

Figure 3 is a section on the line 3—3, Figure 1.

Figure 4 is an enlarged fragmentary elevation, the upper end of the tower showing the carriage in elevated position.

The apparatus for making overhead assemblies comprises a tower made up of front corner posts 10 which are inclined rearwardly and upwardly, and rear corner posts 12 which are herein shown as vertical. The corner posts are interconnected at their lower ends by horizontal frame members 14 and adjacent their upper ends by horizontal frame members 16. Intermediate the frame members 14 and 16, the corner posts are connected by horizontal frame members 18. Carried by the upper frame member 16 is a floor or platform 20 on which the workman stands. The corner posts 10 and 12 extend upwardly above the platform 20 and are interconnected at their upper ends by horizontal frame members 22, thus providing a protective railing surrounding the platform.

Means are provided to facilitate movement of the tower structure over the floor or ground and these means are illustrated as caster wheels 23 which are located adjacent the bottom corners of the tower. The caster wheels may be mounted for free angular movement about vertical axes so that the tower may be moved readily in any direction. The size of the ground wheels 23 illustrated in the figures is suitable for use on a cement floor in a partially completed building and it will be

2

understood that if desired, larger wheels might be employed if the tower were required to be moved over the ground rather than a finished floor.

At the front side of the tower and inclined in conformity with the inclination of the front corner posts 10 are track members 24 adapted to support a carriage mounted generally at 26. As best seen in Figure 3, the track members 24 may be of generally C-shaped cross-section to receive supporting rollers 28 carried by the carriage 26.

The carriage 26, as best seen in Figure 4, comprises a shelf 30 connected at its rear edge to frame members 32 which extend parallel to and lie between the tracks 24. Brace members 34 extend upwardly from frame members 32 to the forward edge of the shelf. The rollers 28 are carried by the frame members 32 and it will be observed in Figure 4 that the supporting rollers 28 are located substantially below the shelf portion 30 of the carriage. It will also be observed in this figure that the tracks 24 extend upwardly to the railing 22, thus when the upper pair of rollers 28 is at the upper end of the track the shelf portion 30 of the carriage is located substantially above the railing 22. This permits the shelf to be raised high enough to position an article carried thereby at proper elevation for direct attachment to supporting structure while it remains supported on the shelf. At the same time, the carriage may be lowered to permit the tower to be moved under depending structure in a building such for example as previously assembled pipes, girders, or the like.

Means are provided for effecting up and down movement of the carriage 26 and this means comprises a drum 36 driven by an electric motor 38 mounted on the tower. Carried by the drum is a cable 40 which extends downwardly from the drum and beneath a sheave 42 and thence upwardly and over a second sheave 44, and thence downwardly substantially in the plane of the trackway where the end of the cable is connected to the carriage 26 adjacent the lower end thereof.

Preferably, control means such as push button switch means illustrated at 46 is provided, and as seen in the figures, this control means is conveniently located on the railing 22 so that the workman may control the raising and lowering of the carriage 26.

The shelf portion 30 of the carriage may be provided with roller means adapted to cooperate with the particular type of articles being assembled. Thus for example, in Figure 1 the shelf portion 30 is illustrated as provided with a multiplicity of small rollers 50 on which a relatively heavy article may be supported and moved freely longitudinally of the shelf. The rollers 50 may be of about the size and construction of roller skate wheels positioned so that the upper surface thereof defines a horizontal flat plate over which articles may be moved longitudinally of the shelf.

Alternatively, the shelf may be provided with spaced pairs of rolls such as illustrated at 52 in Figure 4, and these rolls will be spaced apart longitudinally of the platform so as to support an elongated cylindrical article 60 such as illustrated at 54. The article 54 may for example, be a section of pipe adapted to be threaded to a pipe coupling. With the defined arrangement the carriage is elevated to bring the pipe 54 into alignment with the threaded portion and thereafter the pipe may be threaded 65 by rotating it on the rollers 52.

The improved apparatus for making overhead assemblies permits the most economical and rapid completion of overhead assemblies of various types. By providing a tower of such height that it may be moved freely beneath all existing overhead structure, the tower may be moved readily over the floor or ground to any position.

where assemblies are to be made. At the same time, by providing a carriage having a shelf which may be elevated substantially above any portion of the permanent tower structure, articles carried by the shelf portion of the carriage may be elevated into substantially the exact position in which they are to be assembled. By providing roller means on the shelf of the carriage, movements of the articles carried thereby into exact position are facilitated and, in the case of the rollers 52, suitable rotation of the members may be provided for to permit threading of the articles into assembled position.

Since the elevation of the carriage 26 is under the control of the operator who is standing on the platform 20, it is possible for him to control the raising of the shelf 30 and the article carried thereby into the exact position of elevation required by the assembly. The rearward and upward inclination of the trackway provides for increased stability since upward movement of the carriage results in inward movement thereof, thus causing the loads carried by the shelf of the carriage to be supported more nearly intermediate all of the ground engaging wheels of the tower.

The drawings and the foregoing specification constitute a description of the improved apparatus for making overhead assemblies in such full, clear, concise and exact terms as to enable any person skilled in the art to practice the invention, the scope of which is indicated by the appended claims.

What I claim as my invention is:

1. In apparatus for making overhead assemblies during the construction of buildings, a movable tower, and a carriage carried by and movable relative to said tower, said tower having at the lower corners thereof ground engaging wheels mounted for free angular movement, whereby said tower and carriage as a unit may be moved over the ground in any direction, said tower having at the top thereof a platform for a workman and provided above said platform with a protective railing, an upwardly and inwardly inclined trackway at one side of said tower, said trackway extending from the bottom of said tower to said railing, said carriage being movable along said trackway, said carriage having at its upper end an article supporting portion and provided below said article supporting portion with a downwardly extending supporting framework, means on said supporting framework substantially below the upper end thereof interconnected with and movable along said trackway to guide said carriage during movement thereof relative to said tower, whereby said article supporting portion will be projected above said railing when said means reaches the upper end of said trackway, so that an article on said supporting portion may be assembled with a part of an overhead construction of said building, the degree of inclination of said trackway relative to the upright longitudinal median line of said tower being such that a load on said article supporting portion will be supported intermediate all of the ground engaging wheels aforesaid throughout movement of said carriage lengthwise of said tower.

2. In apparatus for marking overhead assemblies during the construction of buildings, a movable tower, and a carriage carried by and movable relative to said tower, said tower having at the lower corners thereof ground engaging wheels mounted for free angular movement whereby said tower and carriage as a unit may be moved over the ground in any direction, said tower having at the top thereof a platform for a workman and provided above said platform with a protective railing, an upwardly and inwardly inclined trackway at one side of said tower, said trackway extending from the bottom of said tower to said railing, said carriage being movable along said trackway, said carriage having at its upper end an article supporting portion and provided below said article supporting portion with a downwardly extending supporting framework, means on said supporting framework substantially below the upper end thereof interconnected with

and movable along said trackway to guide said carriage during movement thereof relative to said tower, whereby said article supporting portion will be projected above said railing when said means reaches the upper end of said trackway, so that an article on said supporting portion may be assembled with a part of an overhead construction of said building, said article supporting portion having a multiplicity of small rollers on which an article to be assembled with the part aforesaid of an overhead construction of said building may be supported and moved freely relative to said article supporting portion, said rollers being arranged in closely spaced rows, the rollers in each row being axially aligned.

3. In apparatus for making overhead assemblies during the construction of buildings, a movable tower, and a carriage carried by and movable relative to said tower, said tower having at the lower corners thereof ground engaging wheels mounted for free angular movement whereby said tower and carriage as a unit may be moved over the ground in any direction, said tower having at the top thereof a platform for a workman and provided above said platform with a protective railing, an upwardly and inwardly inclined trackway at one side of said tower, said trackway extending from the bottom of said tower to said railing, said carriage being movable along said trackway, said carriage having at its upper end an article supporting portion and provided below said article supporting portion with a downwardly extending supporting framework, means on said supporting framework substantially below the upper end thereof interconnected with and movable along said trackway to guide said carriage during movement thereof relative to said tower, whereby said article supporting portion will be projected above said railing when said means reaches the upper end of said trackway, so that an article on said supporting portion may be assembled with a part of an overhead construction of said building, said article supporting portion having a pair of spaced parallel rolls for receiving thereon for rotation relative to said article supporting portion an article adapted to be assembled with the part aforesaid of an overhead construction of said building.

4. In apparatus for making overhead assemblies during the construction of buildings, a movable tower, a movable carriage, and means for moving said carriage, said tower having two vertical rear corner posts, two front corner posts inclining upwardly and inwardly relative to said rear posts, horizontal frame members interconnecting the posts aforesaid at their lower ends, horizontal frame members interconnecting said posts adjacent their upper ends, a platform for workmen upon the last mentioned frame members, horizontal frame members interconnecting said posts at their upper ends and forming a protective railing about said platform for workmen thereon, ground engaging wheels supporting said tower at the bottom thereof, said wheels being mounted for free angular movement about vertical axes, whereby said tower and carriage as a unit may be moved over the ground in any direction, track members disposed between and inclining in conformity with the inclination of said front corner posts, said track members terminating at and connected to the first and last mentioned horizontal frame members, said carriage having a horizontal shelf provided therebelow with downwardly converging front and rear supporting members, said rear supporting members being between said track members and connected at their upper ends to said shelf at the rear thereof, said front supporting members being terminally connected to said rear supporting members adjacent their lower ends and to said shelf at the front thereof, rollers carried by said rear supporting members adjacent the connection thereof with said front supporting members and engaging said track members, whereby said carriage may move lengthwise of said tower to project the shelf aforesaid above the railing aforesaid, so that an article carried by said shelf may be positioned at the proper

elevation for direct attachment to a part of an overhead construction of said building, the means for moving said carriage relative to said tower including an electric motor mounted on said tower intermediate the upper and lower ends thereof, a drum driven by said electric motor, a sheave carried by one of the first mentioned horizontal frame members, a second sheave carried by said railing and a cable extending from said drum beneath the first mentioned sheave and over the second mentioned sheave to said carriage.

5. In apparatus for making overhead assemblies during the construction of buildings, a movable tower, a movable carriage, and means for moving said carriage, said tower having two vertical rear corner posts, two front corner posts inclining upwardly and inwardly relative to said rear posts, horizontal frame members interconnecting the posts aforesaid at their lower ends, horizontal frame members interconnecting said posts adjacent their upper ends, a platform for workmen upon the last mentioned frame members, horizontal frame members interconnecting said posts at their upper ends and forming a protective railing about said platform for workmen thereon, ground engaging wheels supporting said tower at the bottom thereof, said wheels being mounted for free angular movement about vertical axes, whereby said tower and carriage as a unit may be moved over the ground in any direction, track members disposed between and inclining in conformity with the inclination of said front corner posts, said track members terminating at and connected to the first and last mentioned horizontal frame members, said carriage having a horizontal shelf provided therebelow with downwardly converging front and rear supporting members, said rear supporting members being between said track members and connected at their upper ends to said shelf at the rear thereof, said front supporting members being terminally connected to said rear supporting members adjacent their lower ends and to said shelf at the front thereof, rollers carried by said rear supporting members adjacent the connection thereof with said front supporting members and engaging said track members, whereby said carriage may move lengthwise of said tower to project the shelf aforesaid above the railing aforesaid, so that an article carried by said shelf may be positioned at the proper elevation for direct attachment to a part of an overhead construction of said building, the means for moving said carriage relative to said tower including an electric motor mounted on said tower intermediate the upper and lower ends thereof, a drum driven by said electric motor, a sheave carried by one of the first mentioned horizontal frame members, a second sheave carried by said railing and a cable extending from said drum beneath the first mentioned sheave and over the second mentioned sheave to said carriage, and control means for said electric motor including an electric switch carried by the railing aforesaid so as to be accessible to workmen on said platform.

6. In apparatus for making overhead assemblies during the construction of buildings, a movable tower, a movable carriage, and means for moving said carriage, said tower having two vertical rear corner posts, two front corner posts inclining upwardly and inwardly relative to said rear posts, horizontal frame members interconnecting the posts aforesaid at their lower ends, horizontal frame members interconnecting said posts adjacent their upper ends, a platform for workmen upon the last mentioned frame members, horizontal frame members interconnecting said posts at their upper ends and forming a protective railing about said platform for workmen thereon, ground engaging wheels supporting said tower at the bottom thereof, said wheels being mounted for free angular movement about vertical axes, whereby said tower and carriage as a unit may be moved over the ground in any direction, track members disposed between and inclining in conformity with the inclination

of said front corner posts, said track members terminating at and connected to the first and last mentioned horizontal frame members, said carriage having a horizontal shelf provided therebelow with downwardly converging front and rear supporting members, said rear supporting members being between said track members and connected at their upper ends to said shelf at the rear thereof, said front supporting members being terminally connected to said rear supporting members adjacent their lower ends and to said shelf at the front thereof, rollers carried by said rear supporting members adjacent the connection thereof with said front supporting members and engaging said track members, whereby said carriage may move lengthwise of said tower to project the shelf aforesaid above the railing aforesaid, so that an article carried by said shelf may be positioned at the proper elevation for direct attachment to a part of an overhead construction of said building, the means for moving said carriage relative to said tower including an electric motor mounted on said tower intermediate the upper and lower ends thereof, a drum driven by said electric motor, a sheave carried by one of the first mentioned horizontal frame members, a second sheave carried by said railing and a cable extending from said drum beneath the first mentioned sheave and over the second mentioned sheave to said carriage, said shelf being provided with rollers on which an article to be assembled may be supported and moved relative to said shelf.

7. In apparatus for making overhead assemblies during the construction of buildings, a movable tower, a movable carriage, and means for moving said carriage, said tower having two vertical rear corner posts, two front corner posts inclining upwardly and inwardly relative to said rear posts, horizontal frame members interconnecting the posts aforesaid at their lower ends, horizontal frame members interconnecting said posts adjacent their upper ends, a platform for workmen upon the last mentioned frame members, horizontal frame members interconnecting said posts intermediate the frame members aforesaid, horizontal frame members interconnecting said posts at their upper ends and forming a protective railing about said platform for workmen thereon, ground engaging wheels supporting said tower at the bottom thereof, said wheels being mounted for free angular movement about vertical axes, whereby said tower and carriage as a unit may be moved over the ground in any direction, track members disposed between and inclining in conformity with the inclination of said front corner posts, said track members terminating at and connected to the first and last mentioned horizontal frame members, said carriage having a horizontal shelf provided therebelow with downwardly converging front and rear supporting members, said rear supporting members being between said track members and connected at their upper ends to said shelf at the rear thereof, said front supporting members being terminally connected to said rear supporting members adjacent their lower ends and to said shelf at the front thereof, rollers carried by said rear supporting members adjacent the connection thereof with said front supporting members and engaging said track members, whereby said carriage may move lengthwise of said tower to project the shelf aforesaid above the railing aforesaid so that an article carried by said shelf may be positioned at the proper elevation for direct attachment to a part of an overhead construction of said building, said track members being generally C-shaped in cross section and receiving the rollers of said carriage, the means for moving said carriage relative to said tower including an electric motor mounted on one of the third mentioned horizontal frame members, a drum driven by said electric motor, a sheave carried by one of said first mentioned horizontal frame members, a second sheave carried by said railing, and a cable extending from said drum beneath the first mentioned sheave over the second mentioned sheave to said carriage.

8. In apparatus for making overhead assemblies during the construction of buildings, a movable tower, a movable carriage, and means for moving said carriage, said tower having two vertical rear corner posts, two front corner posts inclined upwardly and inwardly relative to said rear posts, horizontal frame members interconnecting the posts aforesaid at their lower ends, horizontal frame members interconnecting said posts adjacent the upper ends, a platform for workmen upon the last mentioned frame members, horizontal frame members interconnecting said posts at their upper ends and forming a protective railing about said platform for workmen thereon, ground engaging wheels supporting said tower at the bottom thereof, said wheels being mounted for free angular movement about vertical axes whereby said tower and carriage as a unit may be moved over the ground in any direction, track members disposed between and inclining in conformity with the inclination of said front corner posts, said track members terminating at and connected to the first and last mentioned horizontal frame members, said carriage having a horizontal shelf provided therebelow with downwardly converging front and rear supporting members, said rear supporting members being between said track members and connected at their upper ends to said shelf at the rear thereof, said front supporting members being terminally connected to said rear supporting members adjacent their lower ends and to said shelf at the front thereof, and rollers carried by said rear supporting members adjacent the connection thereof with said front supporting members and engaging said track members whereby said carriage may move lengthwise of said tower to project the shelf aforesaid above the railing aforesaid so that an article carried by said shelf may be positioned at the proper elevation for direct attachment to a part of an overhead construction of said building.

9. In apparatus for making overhead assemblies during the construction of buildings, a movable tower, a movable carriage, and means for moving said carriage, said tower having two vertical rear corner posts, two front corner posts inclined upwardly and inwardly relative to said rear posts, horizontal frame members interconnecting the posts aforesaid at their lower ends, horizontal frame members interconnecting said posts adjacent the upper ends, a platform for workmen upon the last mentioned frame members, horizontal frame members interconnecting said posts at their upper ends and forming a protective railing about

said platform for workmen thereon, ground engaging wheels supporting said tower at the bottom thereof, said wheels being mounted for free angular movement about vertical axes whereby said tower and carriage as a unit may be moved over the ground in any direction, track members disposed between and inclining in conformity with the inclination of said front corner posts, said track members terminating at and connected to the first and last mentioned horizontal frame members said carriage having a horizontal shelf provided therebelow with downwardly converging front and rear supporting members, said rear supporting members being between said track members and connected at their upper ends to said shelf at the rear thereof, said front supporting members being terminally connected to said rear supporting members adjacent their lower ends and to said shelf at the front thereof, and rollers carried by said rear supporting members adjacent the connection thereof with said front supporting members and engaging said track members whereby said carriage may move lengthwise of said tower to project the shelf aforesaid above the railing aforesaid so that an article carried by said shelf may be positioned at the proper elevation for direct attachment to a part of an overhead construction of said building, said shelf being provided with rollers on which an article to be assembled may be supported and moved relative to said shelf.
